(57) **CLAIM**

The ornamental design for a watch, as shown and described.

DESCRIPTION

FIG. 1 is an isometric view of a watch, as viewed from the top towards the bottom;

FIG. 2 is a top plan view of the watch;

FIG. 3 is a bottom plan view of the watch;

FIG. 4 is a side view of the watch, as viewed from the left; FIG. 5 is a side view of the watch, as viewed from the right; FIG. 6 is an end view of the watch, as viewed from the front; and,

FIG. 7 is an end view of the watch, as viewed from the back. The broken line showing of the knob, the speaker grill, and the charging port, is for the purpose of illustrating portions of the article and forms no part of the claimed design.

1 Claim, 3 Drawing Sheets
